J. H. PHILLIPS

HAMMER

Filed Jan. 12, 1924

Inventor:
John H. Phillips

U. S. Patent Office

1924

UNITED STATES PATENT OFFICE.

JOHN H. PHILLIPS, OF CHICAGO, ILLINOIS.

HAMMER.

Application filed January 12, 1924. Serial No. 685,885.

My invention belongs to that general class of devices known as hammers, and relates particularly to a hammer attachment or feeding device and controlling means therefor. More particularly it is a device for use in connection with percussion hammers, being especially suited for use on spring operated hammers in which the operator turns a crank or cranks when using the device to 5 retract the spring. However, the device is applicable upon various other types of hammers.

The invention has among its objects the production of a device of the kind described 15 that is simple, convenient, compact, efficient and satisfactory for use wherever found applicable. It has particularly as an object the production of a device that will hold the drill to the work and automatically feed the 20 same and cooperating means for controlling the same.

Many other objects and advantages of the construction herein shown and described will be obvious to those skilled in the art 25 from the disclosures herein given.

To this end my invention consists in the novel construction, arrangement and combination of parts herein shown and described, and more particularly pointed out in the 30 claims.

In the drawings, wherein like reference characters indicate like or corresponding parts:

Fig. 1 is a side elevation of a hammer with 35 my improvement applied thereto;

Fig. 2 is a sectional view taken substantially on line 2—2 of Fig. 1;

Fig. 3 is a sectional view taken substantially on line 3—3 of Fig. 1; and

Fig. 4 is a sectional view taken substantially on line 4—4 of Fig. 1.

Referring to the drawings, in which the spring type of hammer is shown with the preferred form of my attachment applied thereto, 1 represents the hammer barrel containing the usual spring and plunger or hammer head, and 2—2 the operating handles. The hammer carries a chuck 3 of suitable form, in which is mounted a tool 4 of the 50 desired size, shape and type.

I have shown the device in operative relation with the work 5, which for purposes of explanation may be called a ceiling, and 6 may be termed a floor. It may be mentioned, 55 however, that 5 represents the work to be

drilled and 6 any stop or abutment, the device not being limited to use for drilling holes in ceilings, as it may be used to drill in floors or walls. In some cases, 6 might represent a block, scaffold or other support, 60 depending upon the height of the ceiling from the floor. The present device is particularly adapted for use where the ceiling is of some height and where it may be necessary for the operator to stand on a step-ladder or the like in order to handle the tool.

The extension consists of one or more telescoping parts 7 and 8 of the desired size, shape and material, which normally may be freely extended or contracted to vary the 70 length. In the particular device shown, the extension or feeding device is arranged for attachment to the hammer 1, the hammer being comparatively short. This is generally preferred rather than to have part 8 as 75 a part of the hammer. A simple connection is shown, consisting of the part 11 suitably secured to the hammer, as for example by a bolt 12, and which has a part 13 connected as indicated at 14 and is adapted to be secured to part 8 either by threads thereon as shown, or in an equivalent manner. Arranged on the part 8 is a spring 16 of suitable tension, which is shown bearing at either end against the collars 17 and 20. The collar or 80 sleeve 17 is in the form of a clamp and is normally tightly secured in place by a bolt 19 and nut 18 or the equivalent. The clamping member 20 ordinarily is loose on the member 8, but may be tightened to maintain the 85 spring compressed, if desired, by means of the bolt and wing nut 21, similar to the wing nut 18 and bolt 19 on the clamp 17. Mounted on the part 8 is a member 22 which carries an arm 23, the same being shown carried on the 90 pin 24 and secured thereon by a cotter pin or equivalent means. Member 22 may be locked in place when desired by the bolt and nut 22'. The arm or lever 23 is provided with an extending part 25 which is connected to the 95 part 7 by means of a cable or rod 26 and clamping member 27 or equivalent means for the purpose. Generally, I prefer to provide a cable, rod or the equivalent 28 at the free end of arm 23 so that the same may be operated from a distance when required. The collar 22 may be left loose on the member 8 or it may be tightened thereon, but generally when the device is used on a hand-operated 100 hammer, it is left loose so that as the oper-

- ator gives the drill a short back and forth movement while drilling, to change the position of the cutting points or teeth of the drill, the arm will not interfere with him.
- 5 For a power-driven hammer, the collar 22 is usually tightened so that the lever 23 may be used to move the drill, as above described, while drilling. Depressing end of the arm 23 compresses the spring and contracts the
- 10 extension, thereby withdrawing the tool or drill from the hole.
- In using the apparatus, the tool 4 is set at or about the point where the hole is to be drilled, and the lower end of the extension
- 15 set substantially directly below this point, the tension of the spring on the device being controlled by means of the arm or lever 23. Usually the moving and setting up is done from the floor, the tool being set up with the
- 20 drill against the ceiling about where the hole is to be drilled with the bottom under to plumb and released so that the spring pressure will hold the tool upright. The operator can then go up the step-ladder, as drilling is usually done from a step-ladder, or
- 25 other support, and move the drill point to the exact position. It is to be noted that at any time that the drill is removed from the hole for any purpose the device may be released
- 30 against the ceiling so that the entire tool will stand alone until ready to be moved to the next hole. Assuming that the tool is properly set, the operator then turns the handles 2 operating the hammer so as to drill the
- 35 hole, the spring pushing the tool or feeding it. When the hole is drilled to the desired depth, the operator on the ladder, or however he is supported, depresses the lever and withdraws the tool from the hole, inserting
- 40 the expansion bolt, or in the particular case illustrated in which my improved combined drill and expansion shell is shown, he may remove the tool or drill and insert the expander and thence drive the drill back into the hole where it constitutes an expansion shell and remains there. He can then release
- 45 the shell or drill from the chuck and by depressing on the lever 23 moves the tool down so that it is free. It may be particularly
- 50 noted that as he operates the tool, the spring bearing against the collar 17 feeds the tool by applying pressure to the hammer. Obviously, this pressure may be varied by shifting or adjusting the collar 17, or by lengthening part 7. As collar 20 is tightened, all
- 55 pressure of the spring will be between the collars 17 and 20 carried on part 7, so that there will be no tendency of the parts 7 and 8 to fly apart at any time, and the spring will
- 60 be locked against loss if parts 7 and 8 are disassembled.

It should be particularly noted that the extension may be of any length, that is to say, five, ten, twenty, or even more feet, and part

65 7 may be made in one or more sections suit-

ably secured together so that a large variety of lengths are obtained, making the tool applicable for work between different points 5 and 6, or a block or the like may be positioned under part 7 for slight variations of height. 70

The one operator on the ladder can very conveniently control the tool, both in drilling and in changing by employing the lever 23 or the operator may confine himself to the operation of the hammer and interchanging the tools, etc., and the helper down below control the expansion or contraction of the extension by means of the lever 23 and cable 28. This is of importance on work of considerable height, as the operator on the ladder 80 would have to apply the pressure on the tool while the man below is swinging out the end, or the man on the floor would have to lift to compress the spring.

The device is particularly adapted for use 85 by one man as the extension will hold the hammer and drill to the work and automatically feed the drill during the drilling operation while with the controlling mechanism there is provided means for quickly and easily compressing the spring on the extension to withdraw the drill from the hole and to hold the spring under compression while changing drills or tools and moving from hole to hole. As mentioned before, when a 95 power-driven hammer is used, the controlling mechanism, in addition to the functions described, may be used to turn the drill while drilling.

The device saves labor and time, and by 100 making the control of the tool easy, tends to avoid accidents.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned. 110

What I claim as new and desire to secure by Letters Patent is:

1. The combination with a hammer of the kind described, of a feeding device quickly 115 detachable from said hammer, said feeding device comprising extensible cooperating parts, a spring arranged to normally move said parts to extend the same, and means operable by a flexible connection remotely from 120 said device for controlling the operation of said spring.

2. A hammer of the kind described provided with an extension at the rear end, said extension being adjustable lengthwise, spring 125 means arranged to extend the parts of said extension, and means operable remotely from said hammer for compressing said spring and moving the parts to reduce the operative length of the extension. 130

3. The combination with a hammer of the kind described, of an extension comprising two telescoping and relatively adjustable parts connected together, a spring for extending said parts, and a single lever for manually rotating the hammer and for manually contracting said spring, said lever projecting substantially at right angles to said parts when the spring is functionally operative to extend 10 the parts.

4. A hammer controlling device consisting of adjustable parts arranged for attachment to a hammer, spring actuating means therefore, and means for compressing said spring 15 actuating means comprising a lever secured intermediate its ends to one adjustable part, and at one end to the other part, with means attached to the opposite end for operating said lever at a distance therefrom.

5. The combination with a hammer of the kind described, said hammer being provided with a handle part, of extensible cooperating parts for feeding the hammer, one of said parts being provided with a socket for receiving said handle part, a spring arranged to normally move said parts to extend the same, and means operable remotely from said 20

hammer for controlling the operation of said spring.

6. The combination with a hammer of the kind described, of an extension comprising two telescoping and relatively adjustable parts connected together, a spring for extending said parts, and a single lever for manually contracting said spring, said lever being pivoted on one of said parts and having one arm flexibly connected to the other of said parts, the other lever arm being free.

7. The combination with a hammer of the kind described, of an extension comprising two telescoping and relatively adjustable parts connected together, a spring for extending said parts, and a single lever for manually rotating the hammer and for manually contracting said spring, said lever being pivoted on one of said parts and having one arm so connected to the other of said parts as to be normally maintained in a plane perpendicular to said parts, the other lever arm being free.

In testimony whereof, I have hereunto signed my name.

JOHN H. PHILLIPS.
